UNITED STATES PATENT OFFICE

133,173

DESIGN FOR A PORTABLE RADIO

Harold F. Brooks, II, Trenton, N. J.

Application October 9, 1941, Serial No. 103,693

Term of patent 14 years

To all whom it may concern:

Be it known that I, Harold F. Brooks, II, a citizen of the United States, residing at Trenton, in the county of Mercer and State of New Jersey, have invented a new, original, and ornamental Design for a Portable Radio, of which the following is a specification, reference being had to the accompanying drawing, forming a part thereof.

Fig. 1 is a front elevational view of a portable radio showing my new design;

Fig. 2 is a top plan view;

Fig. 3 is a rear elevational view; and

Fig. 4 is a side elevational view with the support member as it appears in extended position.

Figs. 2, 3 and 4 have been illustrated to a somewhat reduced scale and a portion of the strap member omitted therefrom for convenience of illustration.

I claim:

The ornamental design for a portable radio, substantially as shown and described.

HAROLD F. BROOKS, II.
